APRON HOOP

Robert K. Fujioka, Los Angeles, Calif., assignor to Reynolds Industries, Inc., Santa Monica, Calif., a corporation of California

Application April 18, 1955, Serial No. 35,547

Term of patent 3½ years

(Cl. D3—10)

Fig. 1

Fig. 3

Fig. 2

Fig. 4

Fig. 5

Figure 1 is a perspective view of an apron hoop showing my new design;

Figure 2 is a top plan view of the hoop;

Figure 3 is a side elevational view;

Figure 4 is a front elevational view of the hoop in flattened form; and

Figure 5 is a sectional view through the hoop taken at 5—5 in Figure 4.

I claim:

The ornamental design for an apron hoop, substantially as shown.
